TARGET PISTOL

Filed July 22, 1921

UNITED STATES PATENT OFFICE.

HAROLD WESSON AND EDWARD S. POMEROY, OF SPRINGFIELD, MASSACHUSETTS, ASSIGNEES, BY MESNE ASSIGNMENTS, TO SMITH AND WESSON, INC., OF SPRINGFIELD, MASSACHUSETTS, A CORPORATION OF MASSACHUSETTS.

TARGET PISTOL.

Application filed July 22, 1921. Serial No. 486,680.

To all whom it may concern:

Be it known that we, HAROLD WESSON and EDWARD S. POMEROY, both citizens of the United States of America, residing in Springfield, in the county of Hampden and State of Massachusetts, have invented certain new and useful Improvements in Target Pistols, of which the following is a specification.

10 This invention relates to pistols designed particularly for use in target practice, although applicable to other purposes. For such use it is desirable to have a long barrel and a comparatively heavy stock, so

15 that the center of gravity shall be kept as low as possible, in order thereby to minimize the tendency of the recoil to throw up the muzzle in firing. The present invention attains these advantages and also shortens the

20 pistol as much as possible without reducing the length of the barrel from its standard length (of ten inches).

The invention in its preferred form provides a single loading pistol having its barrel hung to the frame on a vertical axis, so that to open the breech the barrel is swung laterally with reference to the stock. This swinging movement operates an extractor for withdrawing the empty shell. The arm is designed to be reloaded by hand. It has a breech block which is fixed integrally to the frame, and a lock is provided for locking the barrel and frame together when the barrel is aligned with the frame in firing position. The hammer is formed as a longitudinally-movable slide, and is preferably drawn back by hand for cocking. The sear operates so nearly at right angles to the hammer as to permit of firing with a light trigger pull, which is desirable in target practice.

The preferred construction is shown in the accompanying drawings, wherein

Figure 1 is a side elevation, partly broken away, in vertical longitudinal mid-section;

Fig. 2 is a horizontal section line on the line 2—2 in Fig. 1, showing the barrel locked fast to the frame, as in Fig. 1;

Fig. 3 is a similar horizontal section, but showing the barrel swung to the position for extracting the spent shell and reloading;

Fig. 4 is a side elevation, on a reduced scale, of the opposite side of the arm from

that shown in Fig. 1, showing the hammer cocked;

Fig. 5 is a side elevation of the hammer;

Fig. 6 is a side elevation of the extractor;

Fig. 7 is a plan and side elevation of the extractor cam.

In the drawings, A is the main frame and B the barrel, which are pivoted together on a vertical axis *a* coinciding with the mid-longitudinal plane of the arm. The barrel accordingly is swingable laterally around this axis to open the breech. The frame A includes the stock, which is shaped and located as in the usual automatic pistols where the magazine is introduced within the stock or grip. The present pistol, however, being preferably a single loader, has no such magazine, the grip portion of the stock being utilized only for the sear and trigger, and their connection. The frame A has the breech block C projecting upwardly from it behind the barrel, and formed preferably integrally with it, this breech block being solid, except for the perforation through which acts the firing pin *b* carried by the hammer D.

The hammer D is shown separately in Fig. 5. It is formed with a longitudinal sliding portion E which may be cylindrical, and which works in a longitudinal guiding recess formed in the frame A beneath the barrel. The rear portion of the slide E projects out through an opening at the rear of the frame, and is formed with a head or upward extension *c* which carries the pin *b*, and is also formed with a cocking grip *d*, by

which the hammer may be conveniently grasped and pulled backward in a straight line for cocking. The head projects in rear of the breech block C. The main spring F, which impels the hammer forward, is shown

as a helical spring housed in a recess bored out within the slide E and reacting rearwardly against a plug *e* which is fastened by a pin *f* to the frame A; and reacting forwardly against a flange on an arrester plug *g* which in turn abuts against a bushing *h* screwed into the front end of the hammer slide E.

The action of the main spring ceases when the arrester plug strikes the abutment in advance of it. The hammer has a slot *i* on opposite sides, through which the stationary pin *f* passes. A rebound

spring *j* is mounted in the hammer socket to the rear of the plug *e*, and acts to press back the hammer after firing.

- The sear *G* is mounted to slide vertically in the frame, being pressed up by a sear spring *h* which reacts downwardly against a screw plug *h'*. The sear is best formed as a cylindrical pin sliding in a cylindrical hole drilled upwardly through the frame. Its movement is limited by a stationary pin *l* in the frame engaging a notch in the sear. The upper end of the sear has a shoulder *m* which engages the cocking shoulder *n* (Fig. 5) on the underside of the hammer. These shoulders may engage in a vertical plane, but preferably are slightly inclined backward, so that the trigger action is not too sensitive. The screw *h'* adjusts the trigger pull.
- 20 The sear is operated by the trigger *H* through an elbow lever *I* pivoted in the frame, its long arm engaging a slot in the trigger, and its short arm formed as a toe entering a notch *p* in the sear so as to press down on a shoulder *q* to withdraw the sear. The trigger *H* is shown as formed with the usual slide *H'* having a parallel longitudinal movement in a slideway formed in the frame. The trigger action is limited in its forward movement by a pin *q'*, and in its rearward movement by the end of the slot in which the slide *H'* moves. The action may be adjusted by making the pin *q'* larger or smaller; or in any other convenient way.

- The barrel is pivoted upon the frame in such manner as to permit it to swing in a horizontal plane for opening the breech, and yet so as to securely lock it to the frame when in the firing position. The barrel turns on an upright pin *r* which may be fastened to either the barrel or frame, but preferably to the barrel, and which is shown as fixedly united at its upper end to the barrel, and as projecting down through a close fitting hole in the frame and receiving a lock nut *r'* on its lower end, whereby to hold down the barrel. The barrel also is formed with undercut projections *s s'*, shown in Fig. 4, which enter corresponding recesses in the frame, these parts being formed in arcs of a circle the center of which is on the axis *a*, as shown in Figs. 2 and 3. Thus the projections *s s'* form in effect trunnion portions which engage under corresponding shoulders on the frame and hold the barrel locked down firmly to the frame in the firing position. For locking the barrel fast in this position, a locking bolt *J* is provided, which is shown as housed in a recess *t* in the lower part of the barrel, pressed out by a spring *t'* which is housed in a recess within the bolt, and the bolt is formed with a lateral arm carrying a finger-piece *J'* lying close against the exterior of the barrel, to be

engaged by the finger or thumb to unlock the barrel from the frame; the arm carrying the finger-piece moves in a slot *u* which is covered over and concealed by the finger-piece *J'*. The end of the bolt *J*, which is preferably beveled, as shown in Fig. 2, enters a correspondingly shaped notch or socket *K* formed in the frame *A*.

The extractor or ejector *L* is shown separately in Fig. 6. It has a sliding portion *L'*, preferably cylindrical, which moves in a correspondingly shaped longitudinal recess formed in the barrel beneath the cartridge chamber. It is pressed forward by a spring *v*, which is shown as a helical spring housed in a chamber bored out within the slide portion *L'* pressing forwardly against the closed end of such chamber and reacting rearwardly against a block or plug *w* which is fastened by a pin *w'* to the barrel, the extractor slide having longitudinal slots *x* through which the pin *w'* passes, and which are of sufficient length to permit the longitudinal movement of the extractor. The extractor *L* projects upwardly from its slide *L'*, this projection fitting into a notch cut in the lower part of the barrel, and being shaped to engage the lower half of the rim of the cartridge shell, so that as the extractor is moved rearwardly relatively to the barrel, it pushes out the spent shell. For giving it this rearward movement coincidently with the swinging movement of the barrel, a cam device is provided, which will now be explained.

Pivoted on the pin *r* is an oscillating extractor cam *M*, shown separately in Fig. 7. This cam is mainly cylindrical in form and has a notch *11* on its upper face, one side of which notch is curved to form a cam *12*. The extractor has a projection *13* which in its normal position enters the notch *11*, this projection having, as shown in Fig. 2, a curved face which coacts with the cam face *12*, so that as the barrel is swung out of line with the frame *A*, and while the cam *M* is held stationary by being locked to the frame, the cam action of these faces against each other pushes back the extractor, so that it is carried out to the position shown in Fig. 3, in which it draws the spent shell out of the barrel and either ejects it or leaves it so far out that it may be easily grasped and pulled out by hand. To accomplish this camming out of the extractor it might suffice to have the cam *M* locked fast to the frame *A* in any suitable manner; but it is preferable to lock it to the frame *A* only temporarily, and for a portion of the swinging movement of the barrel. For this purpose it is formed with a catch or detent *N* which is formed as a slide moving in a straight recess formed tangentially across the lower part of the cam *M*, having on one end a beveled head *14*, and on the other end

a head 15; this head projects sufficiently so that shortly after the beginning of the turning movement of the barrel, it engages a shoulder 16 (Fig. 2) on the frame, whereby it temporarily locks the cam M fast to the frame A, so that the cam face 12 may cam back the extractor, as described. This locking fast continues until, by the further swinging of the barrel, a shoulder 17 on the latter bears against the outer face of the head 15 and presses in the detent N until its head no longer engages the shoulder 16, but passes within the curved recess 18 in the frame A. This releases the cam M and permits the extractor spring to throw forward the extractor, and in so doing to turn forward the cam M, this, however, being an idle movement. This movement is limited by the projecting advance end 19 of the detent N striking the shoulder 20 on the frame, whereby the cam M is again stopped and held stationary, and if the swinging movement of the barrel is continued further (which is unnecessary), the cam M, by reason of the engagement of its face 12 with the tail 13 on the extractor, again projects the extractor. On the return movement of the barrel the cam M is restored to its first position, the curved cam face 14 on the detent N engaging a shoulder 21 on the frame to press back the detent to its original position with its head 15 projecting, ready for the next operation. To prevent accidental movements of the detent N, it is provided with a friction spring 22, being a leaf spring held in a notch in the detent with its ends against the ends of the notch and its bowed middle bearing against the wall of the recess in which the detent moves. As seen in Fig. 2, the pin r is partly cut away to permit the full entry of the tail 13 in the normal position of the extractor.

The operation of the arm will be obvious from the foregoing description. The loading operation leaves the hammer uncocked, and the operator grasps the head d and pulls it back to cock the arm, its position being then as shown in Fig. 4; the pulling of the trigger lowers the sear and releases the hammer, which slides forward, its pin striking the cartridge base and firing the arm; the operator then presses back the locking bolt J and swings the barrel around substantially ninety degrees, in which movement the extractor pushes out the spent shell, which is then removed; the operator then pushes in a new cartridge and restores the barrel to its original position, where it is locked by the spring bolt J. The arm is then ready to be recocked and refired.

The described construction may be varied or modified in many respects, those features which are essential to the invention being defined in the appended claims.

65 The advantages of the new construction will be apparent. The barrel is carried as far back as possible with reference to the stock, so that the arm is shortened without reducing the length of the barrel. The breech is located to the rear of the stock, and the stock is in a desirable position beneath the barrel, with the center of gravity carried as low as possible. The resulting arm has the maximum of accuracy, convenience and compactness, with the minimum of rebound. The lockwork is carried wholly within the stock, and its construction is very simple; the sear spring acts also through the trigger lever as a trigger spring.

We claim as our invention:

1. A pistol comprising a frame and stock formed with a breech block, and a barrel mounted to swing on a vertical axis located forward of the breech block, and a hammer formed as a slide movable longitudinally in a slideway in the frame, the hammer having a lower slide portion entering the slideway in the frame, and an upper exterior head extending to the rear of the breech block, with a firing pin movable through an orifice in the breech block.
2. A pistol comprising a frame and stock formed with a breech block, and a barrel mounted to swing on a vertical axis located forward of the breech block, and a hammer formed as a slide movable longitudinally in a slideway in the frame, with a sear located in upright position in the frame and stock, and mounted to move transversely to the hammer.
3. A pistol comprising a frame and stock formed with a breech block, and a barrel mounted to swing on a vertical axis located forward of the breech block, and a hammer formed as a slide movable longitudinally in a slideway in the frame, with a sear formed as a slide movable transversely to the hammer, located in the frame and stock beneath the hammer slide.
4. A pistol comprising a barrel and frame, the frame having a breech block behind the barrel, and a stock projecting downward beneath the barrel and forward of the breech block, a sliding hammer in the frame, and a sear formed as an upright bar movable in a recess in the stock.
5. A pistol comprising a barrel and frame, the frame having a breech block behind the barrel, and a stock projecting downward beneath the barrel and forward of the breech block, a sliding hammer having a slide portion movable longitudinally in the frame beneath the barrel and having a rear head projecting upward behind the breech block, and a sear formed as an upright bar movable in a recess in the stock.
6. A pistol comprising a frame and barrel pivoted together, a hammer formed as a longitudinally-moving slide, a sear constituting an upright bar engaging said ham-

mer slide at its upper end, a trigger connected to operate said sear, and a sear spring pressing up the sear and pressing back the trigger, with means for adjusting its effective stress to vary the trigger pull.

7. A pistol comprising a barrel and frame, the frame having a breech block behind the barrel, and a stock projecting downward beneath the barrel and forward of the breech block, a sliding hammer in the frame, and a sear movable in the stock, the sear being a cylindrical bar and the stock having a cylindrical bore in which said bar slides.

8. A pistol according to claim 7, the cylindrical bore in the stock closed by a plug, and a sear spring in said bore reacting against said plug.

9. A pistol comprising a frame and barrel pivoted together, a hammer movable in the frame, a sear formed as an upright bar housed in the frame, a sear spring pressing the sear into engagement with the hammer, a trigger connected to operate the sear, and means for varying the trigger pull comprising a screw plug adjustable in the frame and receiving the reaction of said sear spring.

10. A pistol comprising a frame and a barrel pivoted to swing horizontally thereon, an extractor movable longitudinally of the barrel, and means adapted upon the swinging movement of the barrel to operate such extractor to withdraw the shell, and to release the extractor to permit the insertion of a new cartridge.

11. A pistol comprising a frame and a barrel pivoted to swing horizontally thereon, an extractor movable longitudinally of the barrel, a spring for retracting the extractor, and means adapted upon the swinging movement of the barrel to operate such extractor to withdraw the shell, to permit it to spring back for the insertion of a new cartridge.

12. A pistol comprising a frame and a barrel pivoted to swing horizontally thereon, an extractor movable longitudinally of the barrel, and means adapted upon the swinging movement of the barrel to operate such extractor to withdraw the shell, the extractor-operating means comprising a cam having means for locking it to the frame during a portion of the swinging movement of the barrel.

13. A pistol according to claim 12, the extractor-operating means comprising a cam having a detent coacting with the frame and barrel and adapted to lock the cam to the

frame during the initial portion of the swinging movement of the barrel.

14. A pistol comprising a barrel and frame, with a sliding hammer movable in a longitudinal recess in the frame, and having a longitudinal bore, a helical main spring and a helical rebound spring in such bore, a stationary block in said bore between said springs, and a pin fastening said block to the frame, the hammer having a longitudinal slot traversing said pin.

15. A pistol comprising a barrel and frame, with a sliding hammer, a main spring therefor, an arrester piece between said spring and the hammer adapted to strike the frame before the hammer strikes, whereby the spring ceases to impel the hammer, and a rebound spring adapted to move the hammer back after striking.

16. A pistol comprising a frame and barrel, the latter pivoted on a vertical axis, and an extractor carried by the barrel and movable longitudinally thereof with the swinging movement of the barrel, having actuating means deriving motion from the pivot on which the barrel turns.

17. A pistol comprising a frame and barrel, the barrel pivoted on a vertical stud fixed to the frame, an extractor carried by the barrel, and an extractor-operating means pivoted on such stud to move the extractor rearwardly on the barrel as the barrel swings laterally.

18. A pistol comprising a frame and barrel, the latter pivoted on a vertical axis, and an extractor carried by the barrel consisting of a tubular slide movable in a longitudinal recess in the barrel and having a retracting spring housed within it.

19. A pistol according to claim 18, the extractor slide having a longitudinal slot, a pin fixed in the barrel and traversing said slot, and the spring reacting against such pin.

20. A pistol comprising a frame and barrel, the latter pivoted on a vertical axis, the frame having a stock beneath the barrel and a fixed breech block behind the barrel, the stock located forward of the breech block and the pivotal axis of the barrel intersecting the stock, the relative arrangement being such that the weight of the arm is mainly on the stock.

In witness whereof, we have hereunto signed our names.

HAROLD WESSON.
EDWARD S. POMEROY.
